His Attorney.

UNITED STATES PATENT OFFICE.

CHARLES C. ABBOTT, OF PITTSFIELD, MASSACHUSETTS, ASSIGNOR TO GENERAL ELECTRIC COMPANY, A CORPORATION OF NEW YORK.

ELECTRIC TERMINAL.

Application filed August 23, 1921. Serial No. 494,652.

To all whom it may concern:

Be it known that I, CHARLES C. ABBOTT, a citizen of the United States, residing at Pittsfield, in the county of Berkshire, State of Massachusetts, have invented certain new and useful Improvements in Electric Terminals, of which the following is a specification.

My invention relates to improvements in terminal arrangements for electric conductors and has for its object the provision of simple, reliable and economical means for making electric connections.

More specifically, my invention relates to the connection of terminals for heating units of the type described and claimed in my copending application, Serial No. 294,837, filed May 3, 1919, assigned to the same assignee as this invention, although it has application to various types of electrical apparatus.

In carrying out my invention I provide a longitudinal hole in the terminal and an intersecting transverse hole therein. The metallic conducting lead for the resistance element is inserted in the longitudinal hole, and then the terminal is swaged. The swaging operation reduces the diameter of the terminal and likewise the diameters of the longitudinal hole and the portions of the lead in engagement with the walls of the hole. The result is that portions of the lead are forced into the transverse hole at the intersection so as to hold the lead firmly in place. I have also provided a connection between the terminal and the resistance element which consists in passing the end of the resistance element through a transverse hole in the terminal and winding it up on a tapered recess on the terminal so that it is wedged tightly between the terminal and the insulating support in which the terminal is seated.

In the accompanying drawing, Fig. 1 is a view partially in section showing the attachment of terminals in accordance with my invention; Fig. 2 is an enlarged sectional view of the terminal before the swaging operation; Fig. 3 is an enlarged view partially in section of the terminal showing the conducting lead secured thereto; Fig. 4 is an end elevation view of the terminal showing the squared portion; Fig. 5 is a section view along the line 5—5 of Fig. 1 looking in the direction of the arrows, while Fig. 6 is a sec-

tion view along the line 6—6 of Fig. 1 looking in the direction of the arrows.

Referring to Figs. 1, 5 and 6 of the drawing, the heating unit 10 is provided with a cylindrical core 11 of suitable insulating material, such as lava, for supporting the resistance wire 12 and the metallic terminals 13 and 14. The terminals 13 and 14 are inserted in parallel longitudinal holes 13' and 14' in the core, while the resistance wire 12 is wound on the core. To facilitate the attachment of the resistance wire to the terminals, a narrow longitudinal slot 15 intersecting with longitudinal hole 13' is provided in the insulating core. This slot extends the full length of the core and also across the left hand end of the core. A small transverse hole 16 extends into longitudinal hole 14' in the core. The terminals 13 and 14 are provided with projecting leads 17 of suitable conducting material which may be either solid or stranded.

Referring to Fig. 2 of the drawing, the terminal 13 consists of a cylindrical piece of suitable electrically conducting material 80 having a short length 22' at the left hand end reduced in diameter and a tapered peripheral recess 22 near the right hand end. In the right hand end of the terminal are drilled a longitudinal hole 18 slightly larger 85 than the lead 17 and a transverse hole 19 intersecting therewith. The lead 17 is then inserted in the hole 18, and the terminal subjected to a swaging process whereby the diameter of the body of the terminal, not including length 22' and the tapered portion at recess 22, is reduced, as shown in Fig. 3. It will be observed that during the swaging operation, the hole 18 is reduced in diameter 90 and as a result the diameters of the portions of the lead in engagement with the walls of the hole are reduced. The portion 20 of the lead registering with transverse hole 19 is flattened but not reduced in size, however, so that an enlarged flattened portion 20 is 100 formed on the lead around which the walls of the longitudinal hole are tightly swaged. This enlarged portion has projections extending from opposite sides of the lead which are forced into the transverse hole 105 19 so as to hold the lead securely in place against both longitudinal and turning movement and in electrically conducting relation with the terminal. The swaging operation produces a reliable and permanent electrical 110

connection between the terminal and the lead. The maximum depth of the recess 22 after the swaging operation is equal to the diameter of the resistance wire to be used. 5 A transverse hole 21 is now drilled through the terminal at the point of greatest depth of recess 22, and the length 22' squared by means of dies. The diameter of portion 10 22' is such that when squared its section has a diagonal dimension equal to the diameter of the body of the terminal, as shown in Fig. 4.

In the assembly of a heating unit of the type disclosed in Fig. 1, the terminals 13 and 14 constructed as described in connection with Figs. 2 and 3 are inserted squared end innermost in the longitudinal holes 13' and 14' in the core 11, the holes being of such depth that the terminals project 20 slightly. One end of the resistance wire 12 is then passed through hole 21 in the terminal 13 and the terminal turned so as to wind the resistance wire in the recess. After making one complete turn, the resistance 25 wire winds up on the tapered recess until the hole in the core member is filled and the resistance wire secured tightly in good electrical contact with the terminal between the terminal and the core member. The terminal is also secured to the core member at 30 the same time. The resistance wire is then laid in the groove 15 along the length across the left hand end of the core member. In the next step the resistance wire is wound 35 on the core member, suitable insulating space being left between turns, and cut to leave a free end of the required length, which is passed through the hole 16 in the core member and inserted in the hole 21 in terminal 14, the hole 21 having been aligned 40 with hole 16. Terminal 14 is then turned with relation to the core member so as to wind the resistance wire in the recess until a tight connection is made as described in 45 connection with terminal 13, all slack in the resistance wire being taken up at the same time. In case a resistance wire of relatively small diameter is used, the tapered recess in the terminal may not be necessary. The core 50 member with the resistance wire and terminals secured thereto is then placed in the cylindrical casing 23, and powdered heat refractory insulating material 24, such as magnesium oxide, packed between the core 55 member and the casing and around the resistance wire. The end of the casing is closed by a suitable insulating disc 25 through openings in which the leads 17 extend and by a metallic disc 26 having enlarged openings around the leads for insulation therefrom. The walls of the casing are next turned over so as to hold the metallic disc in place. The entire unit is then subjected to a swaging process whereby the 60 65 powdered insulating material is compacted

to a solid, dense mass around the core member and between the turns of the resistance wire as set forth in my aforesaid copending application. The swaging operation causes the core member to collapse and flow somewhat and thus compresses it tightly around the terminals so as to secure the terminals against turning movement with relation to the core member by reason of their squared ends. 70

It will be observed that by means of my invention the terminals are connected to the resistance wire and the leads in a very simple, reliable and economical manner and without the use of brazed joints. The terminal can be inspected through the transverse hole to determine whether the lead is properly in place during the swaging operation. Obviously, my invention has application to various types of heating units 80 85 other than the specific type described herein.

In accordance with the provisions of the patent statutes, I have described the principle of operation of my invention, together with the apparatus which I now consider 90 to represent the best embodiment thereof, but I desire to have it understood that the apparatus shown is only illustrative and that the invention can be carried out by other means. 95

What I claim as new and desire to secure by Letters Patent of the United States, is:—

1. The method of securing a terminal to an electric conductor which consists in forming intersecting holes in said terminal, inserting an electric conductor in one of said holes, and reducing the cross section of the terminal until the conductor is forced into the other hole at the intersection and locked in place. 100

2. The method of securing a terminal to an electric conductor which consists in forming a longitudinal hole in the terminal and a transverse hole intersecting therewith, inserting the conductor in the longitudinal 110 hole, and reducing the diameter of the terminal until an enlarged portion extending into said transverse hole at the intersection is formed on the conductor to lock it in place. 115

3. A terminal for electric conductors comprising a terminal member recessed to receive the conductor, and provided with an intersecting recess into which the conductor is forced to lock it in place. 120

4. A terminal for electric conductors comprising a terminal member recessed to receive the conductor and provided with an intersecting recess into which the conductor is forced to lock it in place by reducing the 125 cross section of the terminal.

5. A terminal for electric conductors comprising a terminal member provided with a longitudinal recess to receive the conductor, and an intersecting recess into which 130

the conductor is caused to extend to lock it in place by reducing the diameter of the terminal by swaging.

6. The combination with an insulating support of a terminal arranged to be inserted therein, comprising a terminal member provided with a tapered portion on which the resistance wire is wound until it is locked between the terminal and the insulating support.
7. The combination with an insulating

support of a terminal arranged to be inserted therein, comprising a terminal member provided with a tapered portion having a transverse aperture into which the resistance wire is inserted and wound up on the tapered portion by turning the terminal until it is wedged between the terminal and the insulating support. 15

In witness whereof, I have hereunto set my hand this 20th day of Aug., 1921.

CHARLES C. ABBOTT.
